US00D996541S

(12) United States Design Patent (10) Patent No.: US D996,541 S
(45) Date of Patent: * Aug. 22, 2023

(54) GOLF TEE SUPPORT

(71) Applicant: Nicholas Christopher Margin,
Dianella (AU)

(72) Inventor: Nicholas Christopher Margin,
Dianella (AU)

() Term: 15 Years

(21) Appl. No.: 29/767,467

(22) Filed: Jan. 22, 2021

(30) Foreign Application Priority Data

Aug. 5, 2020 (AU) 202014252
(51) LOC (14) Cl. 21-02

(52) U.S. Cl.

USPC D21/718; D21/717

(58) Field of Classification Search

USPC D21/717, 718, 793, 794, 796, 839, 840;
D19/101, 115, 123, 129, 1, 54, 161, 162,
D19/163; D8/1, 349, 388, 389
CPC B43K 24/082; B43K 24/04; A63B 57/10;
A63B 57/13; A63B 57/15; A63B 57/18;
A63B 57/19

(57) CLAIM

The ornamental design for golf tee support, as shown and described.

DESCRIPTION

FIG. 1 is a right side view of my design.

FIG. 2 is a front side view of my design.

FIG. 3 is a top view of my design.

FIG. 4 is a cross-sectional view of my design taken in the direction of lines 4-4 of FIG. 3.

FIG. 5 is a bottom view of my design.

FIG. 6 is a left side view of my design.

FIG. 7 is a rear view of my design.

FIG. 8 is a top perspective view of my design.

FIG. 9 is a bottom perspective view of my design; and, FIG. 10 is a right side view of the golf tee support in an environment of use.

The broken lines in FIG. 10 are for purposes of illustrating environmental subject matter only and form no part of the claimed design.

1 Claim, 10 Drawing Sheets
